ACCESS HOLE COVER SECURING MEANS
Donald C. Baker, Burlington, Iowa, assignor to J. I. Case
Company, Racine, Wis., a corporation of Wisconsin
Filed Jan. 8, 1963, Ser. No. 250,153
6 Claims. (Cl. 220—35)

The present invention relates to covers or closures, and particularly to closures for access openings in protective housings of a rugged nature for protecting units of a relatively delicate character from damage. In the illustrative embodiment disclosed, the housing is intended to enclose and protect an automotive radiator, although the enclosure and protection of any unit requiring protection is considered as within the contemplation of the invention, whereby ready access to the unit within is important, but without impairing the protection afforded by the housing or shell.

As an example, the radiator on a tractor-loader is subject to the hazard of rocks or other debris occasionally falling out of the loader bucket, and which could do great damage to the radiator if it were not protected.

On the other hand, the purpose of the protective shell would be largely defeated, if the usual filler neck and cap of the radiator were to be exposed through the necessary opening in the shell. A cover or closure is therefore necessary for such opening. However, any closure for such opening should be substantially instantly removable without tools, but when in place should be rugged enough to withstand the battering to which the shell is exposed from time to time.

Furthermore, the closure must not be readily dislodged by objects falling on or brushing against it or the shell.

With these requirements in view, an object of the invention is to generally improve closures of this class.

A further object is to provide a closure for a protective housing or shell, and which closure is adapted to withstand substantial impacts without damage.

Further objects are to provide such a closure which is readily removable, which is not likely to become displaced by falling stones or the like, or by being brushed by the branches of trees, etc., which is resiliently anchored in closed or open position, and which has an intermediate position in which it will remain partially open for facilitating a manufacturing operation, as painting.

In the drawings,

FIGURE 1 is a plan view of a fragment of the top of a protective shell of the type involved with a closure thereon embodying the invention, and

FIG. 2 is a sectional view on the line 2—2 of FIGURE 1.

The closure is applied to a protective housing or shell having an upper wall 10, a front wall 12 and a side wall 14, the several walls, in the present illustrative embodiment, enclosing an automotive type radiator, a portion 16 which is shown disposed within the enclosure formed by the walls and beneath a filler opening 18. Portion 16 has a filler neck 20 of well known type which is closed by a suitable removable cap 22 which may also be of any well known type. Cap 22 is positioned to be easily reached and removed by reaching the hand through opening 18 when a suitable cover 24 is removed.

Walls 10 and 14 constitute the protective structure of the shell, and in the illustrative embodiment are made of heavy boiler plate suitably welded together to form a box-like enclosure, it being understood that another side wall corresponding to wall 14 is provided, but which is removed and not visible in the drawings. Wall 12 is not necessarily as rigid as walls 10 and 14, but is sufficiently strong to protect the vertical front face of radi-

2

ator 16 and, as will be understood, is perforated in a manner to admit the necessary cooling air to the radiator. Wall 10 preferably overhangs or extends beyond the upper edge of wall 12 and tends to shield the latter from objects falling on wall 10, and which might otherwise damage or displace wall 12.

Access opening 18, as stated, is positioned to allow access to filler cap 22, and therefore is, in the present instance, formed in the substantially horizontal portion of wall 10, although it is to be understood that the invention might also be used in connection with protective enclosures wherein the necessary access opening was in a wall other than a horizontal wall.

Cover 24 comprises a plate 26 of heavy sheet metal or material which will be rugged enough over the comparatively limited area of opening 18 to withstand the impact of rocks, etc., falling onto wall 10, if they happen to hit closure 24. Plate 26 will not need to be as thick as wall 10, since it is supported on all sides by the margins of opening 18. However, it is made of heavy material, in the present illustrative embodiment, of a thickness of $\frac{1}{8}$ inch.

Plate 26 has an extension portion 28 beyond the margin of opening 18, and providing an aperture, slot or notch 30. Notch 30 is bridged by a hinge pin 32 which is permanently fastened in place in any suitable manner on the side of plate 26 away from wall 10; in the closed position of the cover; in the present instance as by welding 34. A U-bolt generally designated as 36 has a bight portion 38 disposed above hinge pin 32. It also has legs 40 and 42 extending downwardly from bight portion 38 through spaced openings or bolt holes 44 and 46 formed in wall 10, spaced from opening 18, and registering with slot 30. Extension 28 of plate 26 projects as aforementioned not only beyond the margin of opening 18, but also a slight distance beyond the hinge pin 32.

U-bolt 36 has a spring 48 on leg 40 and a spring 50 on leg 42, spring 48 being compressed against the underside of wall 10 by means of an anchoring or adjusting means, in the present instance a nut 52. In similar manner, spring 50 is compressed against plate 10 by a nut 54. The reaction of springs 48 and 50, yieldingly maintains bight 38 against hinge pin 32, thereby yieldingly maintaining plate 26 in contact with wall 10, covering opening 18 and shielding filler cap 22 from falling debris.

Plate 26 has an extension 56 in the present instance diametrically opposite extension 28, and having an upturned edge portion 58, which may be readily gripped even by a gloved hand. Upward force exerted on extension 56 will tilt plate 26 generally about hinge pin 32. However, the initiation of such movement will cause downward pressure of an edge portion 60 of above-mentioned extension 28 against wall 10, since extension 28, as stated, extends beyond hinge pin 32. Edge 60 therefore becomes a fulcrum and causes hinge pin 32 to be raised, thereby elevating bight portion 38 and compressing springs 48 and 50. This motion continues to a position A, indicated by dotted lines; whereupon hinge pin 32 will have reached its highest possible position. Continued movement of plate 26 will permit downward movement of hinge pin 32 (and also bight 38) as the whole fulcrums about edge portion 60, springs 48 and 50 expanding while maintaining contact between bight 38 and hinge pin 32. Plate 26 will ultimately take a nearly horizontal position opposite to its closed position, as indicated in dotted lines at B, in which hinge pin 32 is directly in contact with wall 10, and plate 26 is entirely clear of opening 18.

Reverse motion of plate 26 will again raise bight 38, the latter being yieldably urged downwardly to tend to restore plate 26 to its full line position, as soon as above-mentioned position A is passed. It is to be noted that, during the swinging of plate 26 in the region of po-

sition A, edge portion 60 will be forced to slide on the upper surface of wall 10, while under substantial downward pressure from springs 48 and 50. The resulting friction will hold plate 26 quite dependably in the near position A.

The alignment of holes 44 and 46 with slot 30, together with the presence of legs 40 and 42 therein serves to maintain plate 26 against sliding sideways into a position misaligned with hole 18, but to make assurance doubly sure, a stud 62 is fixed in position projecting upwardly from wall 10, preferably diametrically opposite bolt holes 44 and 46, and plate 26 is provided with an opening 64 which registers with stud 62 when plate 26 is in closed position. Plate 26 cannot be sidewardly displaced except to the extent of any clearance between stud 62 and opening 64. Therefore, plate 26 will withstand substantial side shocks, and the brushing of heavy objects across it in a sideward direction without becoming displaced and without introducing extreme stresses or pressures into the U-bolt parts or surfaces in contact therewith.

The operation of the device is thought to be clear from the foregoing, but it is pointed out that the rounded upwardly projecting portion of bite 38, and the upturned portion 58 of extension 56 are both shaped to deflect objects such as tree limbs which may brush against them in the normal progress of the vehicle on which the device is used. The closure is virtually instantly raised out of the way when it is desired to service radiator 16, and remains in position B where it does not encumber opening 18. When the cover is returned to closed position, opening 64 automatically registers with stud 62 by reason of the guiding effect of U-bolt 36 in engagement with holes 44 and 46 as well as slot 28. Plate 26 is readily placed in position A where it will remain with sufficient assurance by reason of the frictional contact of edge portion 60 with the top of wall 10. In the process of manufacture, this facilitates the painting of both sides of plate 26 during a single operation.

From the above, it will be apparent that a device has been provided which will accomplish the objects of the invention, and what is claimed as new, and desired to be secured by Letters Patent of the United States is:

1. In a closure for a protective housing of the type providing an upwardly directed opening, and bolt holes spaced radially of the opening, the combination with said housing of a

plate larger than said opening, and having a portion overlying said spaced bolt holes and providing a notch registering with said spaced bolt holes, a hinge pin bridging said notch and fixed in position on the upper surface of said plate, said hinge pin being

spaced inwardly from the edge thereof, a

U-bolt having a bight portion disposed about said hinge pin and a leg portion extending downwardly through each of said spaced bolt holes, one on each side of said hinge pin, a

spring disposed about each leg portion beneath said housing, and

means on said leg portions engaged with said springs in position to maintain them compressed between said means and the under side of said housing.

2. In a closure for a protective housing of the type providing an access opening, and bolt holes spaced radially of the opening, the combination with said housing of a

plate larger than said opening, and having a portion overlying said spaced bolt holes and providing a notch registering with said spaced bolt holes, a hinge pin bridging said notch and fixed in position on the upper surface of said plate, said hinge pin being spaced inwardly from the edge thereof, a

U-bolt having a bight portion disposed about said hinge pin and a leg portion extending inwardly through said

through each of said spaced bolt holes, one on each side of said hinge pin, a spring disposed about each leg portion beneath said housing, and means on said leg portions engaged with said springs in position to maintain them compressed between said means and the inner side of said housing.

3. In a closure for a protective housing of the type providing an upwardly directed opening, and bolt holes spaced radially of the opening, the combination with said housing of a

plate larger than said opening, and having a portion overlying said spaced bolt holes and providing a notch registering with said spaced bolt holes, a hinge pin bridging said notch and fixed in position on the upper surface of said plate, said hinge pin being spaced inwardly from the edge thereof, a

U-bolt having a bight portion disposed about said hinge pin and a leg portion extending downwardly through each of said spaced bolt holes, one on each side of said hinge pin, a

spring disposed about each leg portion beneath said housing,

means on said leg portions engaged with said springs in position to maintain them compressed between said means and the under side of said housing, a stud fixed on said housing beyond the margin of said opening opposite said bolt holes, said plate having a portion overlying said stud, said portion providing an opening into which said stud projects when said plate is in place closing said opening.

4. In a closure for a protective housing of the type providing an upwardly directed opening, and bolt holes spaced radially of the opening, the combination with said housing of a

plate larger than said opening, and having a portion overlying said spaced bolt holes and providing a notch registering with said spaced bolt holes, a hinge pin bridging said notch and fixed in position on the upper surface of said plate, said hinge pin being spaced inwardly from the edge thereof, a

U-bolt having a bight portion disposed about said hinge pin and a leg portion extending downwardly through each of said spaced bolt holes, one on each side of said hinge pin, a

spring disposed about each leg portion beneath said housing,

means on said leg portions engaged with said springs in position to maintain them compressed between said means and the under side of said housing, a stud fixed on said housing beyond the margin of said opening opposite said bolt holes, said plate having a portion overlying said stud, said portion providing an opening into which said stud projects when said plate is in place closing said opening, and said portion having an

upturned edge positioned to serve as a handgrip for removing said plate from said opening.

5. In a closure for a protective housing of the type providing an opening to be closed, the combination with said housing of a

plate larger than said opening and having a portion extending substantially beyond the margin of said opening and providing a notch, a

hinge pin bridging said notch and fixed in position on the surface of said plate opposite to said protective housing, said hinge pin being spaced inwardly from the edge of said extending portion, a

U-bolt having a bight portion disposed about said hinge pin and leg portions extending inwardly through said notch and through said housing, one on each side of said hinge pin, a

spring disposed about each leg portion on the side of said housing away from said plate, and means on said leg portions engaged with said springs in position to maintain them compressed between said means and said side of said housing.

6. In a closure for a protective housing of the type providing an opening to be closed, the combination with said housing of a plate larger than said opening and having a portion extending substantially beyond the margin of said opening and providing an aperture, a hinge pin bridging said aperture and fixed in position on the surface of said plate opposite to said protective housing, a

5

15

U-bolt having a bight portion disposed about said hinge pin and leg portions extending inwardly through said aperture and through said housing, one on each side of said hinge pin, a

spring disposed about each leg portion on the side of said housing away from said plate, and means on said leg portions engaged with said springs in position to maintain them compressed between said means and said side of said housing.
